UNITED STATES PATENT OFFICE.

ARTHUR F. POOLE, OF WHEELING, WEST VIRGINIA.

PARTY-LINE TELEPHONE SYSTEM.

No. 878,017.

Specification of Letters Patent.

Patented Feb. 4, 1908.

Application filed February 20, 1905. Serial No. 246,404.

To all whom it may concern:

Be it known that I, ARTHUR F. POOLE, a citizen of the United States, residing at Wheeling, in the county of Ohio and State of West Virginia, have invented a certain new and useful Improvement in Party-Line Telephone Systems, of which the following is a full, clear, concise, and exact description, reference being had to the accompanying drawings, forming a part of this specification.

10 My invention relates to party line telephone systems and particularly to improved locking-out means therefor.

My improved system can be applied to 15 party lines to which are connected any number of substations, and the invention consists broadly in providing at each substation a high resistance and a low resistance path for the actuating current flow. Upon actuation 20 of apparatus at a calling substation the low resistance path is eventually connected in circuit and the pressure of the system greatly reduced, whereby the current, which would flow through the high resistance path 25 at another substation of the same party line upon an attempt to listen-in, would be insufficient to cause actuation of apparatus controlled by the high resistance circuit whereby the telephonic apparatus at the 30 listening-in substation is maintained in an inoperative condition. More specifically, I employ at each substation a relay provided with a high resistance winding and a low resistance winding. The armature of this relay 35 normally closes a short circuit about the telephonic apparatus. Upon removal of the receiver from its hook at a calling substation the relay is primarily energized through a circuit including the high resistance winding, 40 whereupon the armature is attracted to open the short circuit about the telephonic apparatus and to close a short circuit about the high resistance winding, the telephonic apparatus being then connected in a circuit including 45 the low resistance winding, and the armature will remain attracted. The current supply may be fed from a central energy battery or from local sources. This low resistance path greatly reduces the strength of the current 50 flowing through the party line, and upon an attempt of a second party to use the line the current will be insufficient to actuate the relay at the substation through the high resistance winding, and, therefore, the short circuit about the telephonic apparatus at this

second substation will remain unbroken and thus any second subscriber will be locked out.

The calling subscriber on a party line may desire communication with another subscriber connected with the same party line, 60 and each substation, therefore, is provided with switching means for rearranging the circuits to allow such connection. The calling subscriber wishing communication with the other subscriber on the same line actuates 65 a switch or presses a button whereby to open a switch or presses a button whereby to open the short circuit about the high resistance winding, and the circuits then will be such that the path through the calling substation will include the high and low resistance 70 windings and the telephonic apparatus in series. Thus the second subscriber, after having been signaled by the central operator, removes his receiver from the hook, and, as the current flow over the line is now sufficient, owing to the high resistance path through the calling substation, the relay at the called substation will be actuated to open the short circuit about the telephonic apparatus and conversation can now be carried on. 80 I also provide means preferably in the form of a condenser which is bridged about the high resistance apparatus at the calling substation to more readily convey voice currents through the telephonic apparatus.

85

Any number of subscribers may be connected to a single party line, and any selective ringing system may be used in conjunction with this locking-out arrangement.

90 My invention will be better understood by referring to the accompanying drawings, in which

Figure 1 shows one arrangement of circuits, and Fig. 2 shows a slightly modified arrangement thereof.

95

In both figures I have shown party lines X and Y connected with the central exchange C, each line terminating in a spring jack 1 and normally connected with the central source 2 through an indicating signal 3. A 100 record circuit D is provided at the central exchange for connecting party lines together and includes well known apparatus such as the operator's listening key 4 and ringing keys 5 and 6 suitably connected with the 105 source 7 of ringing current. A supervisory signal 8 is also shown.

In Fig. 1 each substation is provided with the usual apparatus consisting of the switch hook 9, receiver 10, transmitter 11, and 110

primary and secondary windings 12 and 13 of an induction coil. The switching apparatus, actuated upon removal of the receiver from the hook is associated with the actuating button 14 extending from the hook and engaging actuating springs 15 and 16 normally engaging respectively the ground contact 17 and the inner contact 18, but adapted when the receiver is raised to engage respectively the inner contact 19 and the outer contact 20, a condenser 21 being connected to these actuating springs. In addition to this apparatus there is provided a relay *r* having a high resistance winding 22 and a low resistance winding 23. The armature of this relay consists of the two arms 24 and 25 insulated from each other. The actuating lever 26 of the key *k* is connected to a terminal of each of the relay windings, while the contact 27 normally engaged by the lever 26 is connected with the armature arm 24. The transmitter and primary winding are connected to the switch hook and with the armature arm 25, the switch hook being also normally directly connected with the arm 25 through the back contact 28 and conductor 29. The other terminal of the low resistance winding 23 connects with the switch hook through the transmitter and primary winding, and also connects with the inner contact 19 of the hook switching mechanism. The other terminal of the high resistance winding connects with the front contact 30 of the armature and with the line limb *a*, this line limb connecting also with the contact 20 of the hook switching mechanism. The line limb *b* connects with the switch hook contact 31 and also through the signal bell 32 with the inner contact 18. Thus the conductor 29 normally short circuits the telephonic apparatus, while the signal bell 32 is connected from one line limb through the condenser to ground, and for the purpose of illustration I have shown a two party selective system. In accordance with this arrangement and for the purpose of ringing either of the two substations selectively the keys 5 and 6 at the central exchange serve to connect ringing current from either line limb to ground, thus causing actuation of the signal bell either at substation A or at substation B as desired.

The operation of this arrangement is as follows: Suppose the subscriber at substation B wishes to converse with the subscriber at substation A' connected with the line Y. He removes the receiver from the hook, whereupon current will flow from the line limb *a* through the switch hook and for an instant will flow through the short circuiting conductor 29, through contact 28 and armature arm 25, and through conductor 33 to conductor 34, but subsequently will flow through the primary winding and transmitter to the conductor 34, and from thence

serially through the low and high resistance windings to the line limb *b*. The relay, therefore, is actuated and its armature attracted to open the short circuit about the primary winding and transmitter and to close about the high resistance winding the short circuit path including the contact 30, arm 24 and the key *k*. The line limbs being thus closed through the substation B, the indicator 3 connected with the line X will be actuated, whereupon the operator connects the cord circuit with the spring jack 1 and ascertains that communication which is desired with the subscriber at substation A' on the line Y. Upon actuation of the proper ringing key the bell at the called substation is rung, and upon removal of the receiver thereat from the hook, the relay will be energized to open the short circuit about the telephonic apparatus, and conversation can now be carried on between the substations B and A'.

Owing to the short circuiting path about the telephonic apparatus every other subscriber on the party line X will be locked out unless the relay be actuated to open this short circuiting path. Should another subscriber remove his receiver from the hook current from the line would have to flow serially through the relay windings, but owing to the low resistance path between the line limbs at the calling substation B, the current strength will be insufficient to cause suitable actuation of the relay at the listening-in substation, and the short circuiting path at this substation will not be opened and consequently all other parties, with the exception of the calling party, are effectively locked out, and this would be the case no matter how many substations were connected with the party line. It is desirable, however, in party line systems, that one party on a telephone line be able to converse with another party connected to the same line, but unless some means be provided in this lock-out arrangement just described, such conversation cannot be accomplished. I provide, however, the switch or key mechanism *k* and this key is included in the short circuiting path about the high resistance winding. Should subscriber at substation B desire communication with the substation A on the same line instead of with substation A' on another line, central would inform him to actuate the key *k* thereupon to open the short circuit about the high resistance winding. This, however, again causes serial inclusion in circuit of the high and low resistance windings and the transmitter and primary winding, the armature of the relay remaining attracted. Thus the current flow over the line limbs instead of being drained through the low resistance path is again of sufficient strength to actuate the relay at the substation A upon removal of the receiver.

by the subscriber thereat in response to the signal sent by the central exchange operator. The subscriber at B maintains depression of the key *k* until he gets response from the subscriber at A and then upon release of the key the current flow at both the stations will include only the low resistance winding and the current will be sufficient to maintain both relays active. Owing to the serial inclusion of all these windings upon depression of the key at substation B, there is considerable impedance and difficulty may be encountered therefore in receiving the telephonic voice currents. However, the condenser 21 upon release of the switching hook is bridged about the relay windings through the path including the conductor 35, contact 20, actuating spring 16 through the condenser, spring 15, contact 19 and conductor 34, the condenser affording an easy path for the voice currents. Normally, however, the condenser is connected in the ground circuit from a line limb including the signal bell 32, the ground connection, however, being removed upon release of the switch hook.

In Fig. 2 is shown a slight modification of the circuit arrangements. Instead of automatically actuating switching mechanism upon movements of the switch hook this switching mechanism is incorporated in the key *k*, to be manually actuated. This key consists of the actuating springs 36 and 37, the inner springs 38 and 39 normally engaged thereby and the outer alternate contact springs 40 and 41. The spring 36 is connected with the armature 24 of the relay, and the inner contact spring 38 is connected at one terminal of each winding. The condenser 21 is connected to the actuating spring 37 and the armature contact spring 40, this condenser circuit being grounded, as shown. The inner contact spring 39 is connected through the signal bell 32 with one of the line limbs. The condenser, therefore, instead of being continuously connected in circuit upon release of the receiver hook in Fig. 1, is bridged about the relay windings only upon depression of the manual switch or key *k*. In this modified arrangement also the short circuit conductor 29 bridges the primary winding and transmitter and also the low resistance winding 23 of the relay. The operation with this circuit arrangement is as follows: The subscriber at B desiring communication, for instance with the substation A' on the line Y, raises his receiver, whereupon current flows from the line limb *a* to the receiver hook 9 and instantaneously passes mostly all through the short circuit conductor 29, contact 28, armature 24, through the key *k* and through the high resistance winding. The relay being energized will open the short circuit path about the telephonic apparatus and the low resistance winding, but will close a short circuit path about the high resistance winding, this

path including the front contact 30, armature 24 and springs 36 and 38. The current now flows between the line limbs, from the line limb *a* through the primary winding and transmitter, through the conductor 27, low resistance winding 23, key springs 36 and 38 to armature 24 and from contact 30 to the line limb *b*. The operator receiving the call at the indicator 3 ascertains the connection desired and accordingly rings substation A', and upon the subscriber at A' removing his receiver from the hook, he will be connected for conversation with the subscriber at B. In the same manner as in Fig. 1, any other subscriber connected with the line X cannot listen-in owing to the inoperative condition of this telephonic apparatus which remains short circuited until actuation of the relay, but, owing to the low resistance path between the limbs at the substation B, the current strength is insufficient to actuate any other relay on the line. Subscriber B, however, desiring communication with another subscriber on the line X, for instance as A, must actuate the key *k* which will open the short circuit about the high resistance winding and will cause the high resistance winding to be included serially in circuit with the low resistance winding and the transmitter and primary winding. The relay at the called substation A will then receive sufficient current to be actuated upon removal of the receiver from the hook in response to a calling signal sent from the central exchange. Actuation of the key at substation B also will connect the condenser 21 in bridge of the relay windings, and when the subscriber at A answers, the voice currents will readily pass through the condenser and through the telephonic apparatus at B. Having obtained connection with A, B may release the key and conversation may be carried on in the ordinary manner, the only impedance in these circuits being the low resistance winding and the primary winding which is not sufficient to hinder free transmission of the voice currents.

Although I have shown selective means at the central exchange adapted only for selectively signaling two party subscribers, I need not be so limited, as any selective system may be employed in connection with the locking-out feature as the bell circuits at the substations are entirely distinct from the locking-out circuits. This locking-out feature can, therefore, be applied to any style telephone since the sole connection between the lock-out apparatus and the telephone apparatus is an electrical one, and it may readily, therefore, be installed in existing systems. The same condenser which is used in the usual manner in the bell circuit, may serve to carry the voice currents about the impedance windings. There are also no additional connections or apparatus neces-

sary at the central exchange. No additional operations are necessary to be performed by the exchange operator, except in cases where one subscriber wishes communication with another subscriber on the same line, which is comparatively rare and in which case it is necessary only for the exchange operator to notify the calling subscriber to actuate his key.

10 Many changes and modifications may be made in the arrangement of the apparatus and circuits without departing from the spirit of invention, and I do not, therefore, wish to be limited to the precise arrangement shown, but,

Having described my invention, I claim as new and desire to secure by Letters Patent:

1. In a party line telephone system, the combination with a party line, of a plurality of substations connected therewith, telephonic apparatus and a relay at each substation, said telephonic apparatus being inoperative when said relay is inert, a low resistance path and a high resistance path for including said relay, actuation of said relay causing the telephonic apparatus to become operative, and a source of current for supplying current flow through said paths, the current flow from said source when the low resistance path is included in circuit at one substation being insufficient to actuate the relay at any other substation, whereby the telephonic apparatus at any other substation remains inoperative.

35 2. In a telephone system, the combination with a party line, of a plurality of substations connected therewith, a relay and telephonic apparatus at each substation, said telephonic apparatus when said relay is inert being rendered inoperative, a low resistance winding for said relay included in the relay circuit, a high resistance also included in the relay circuit, energization of said relay at one substation causing the telephonic apparatus thereto to be rendered operative and the high resistance in the relay circuit to be removed from circuit, a source of current for supplying said line and the substation circuits, the current flow upon energization of the relay at the one substation being insufficient to cause actuation of relays at other substations connected with the line, whereby the telephonic apparatus at the other substations is maintained in an inoperative condition.

55 3. In a telephone system, the combination with a party line, of a plurality of substations connected therewith; telephonic apparatus at each substation, a relay at each substation provided with a low resistance winding and a high resistance winding, said telephonic apparatus when said relay is inert being rendered inoperative, and a source for supplying current to the line, current flow through said relay upon actuation of

switching apparatus at one substation causing energization of said relay to short circuit the high resistance winding from circuit, the current flow from said source being thereupon of insufficient strength to cause actuation of relays at other substations through the high resistance winding.

4. In a telephone system, the combination with a party line, of a plurality of substations connected therewith, telephonic apparatus at each substation, a relay at each substation provided with a low resistance winding and high resistance winding, said telephonic apparatus when said relay is inert being rendered inoperative, a source for supplying current to the line, current flow through said relay upon actuation of switching apparatus at one substation causing energization of said relay to short circuit the high resistance winding from circuit, the current flow from said source being thereupon of insufficient strength to cause actuation of relays at other substations through the high resistance winding, and means at the first substation for causing reinclusion in circuit of the high resistance winding whereby the relays at other substations may be actuated.

5. In a telephone system, the combination with a party line, of a plurality of substations connected therewith, a relay and telephonic apparatus at each substation, said telephonic apparatus when said relay is inert being rendered inoperative, a low resistance winding for said relay included in the relay circuit, a high resistance also included in the relay circuit, energization of said relay at one substation causing the telephonic apparatus thereto to be rendered operative and the high resistance in the relay circuit to be removed from circuit, a source of current for supplying said line and the substation circuits, the current flow upon energization of the relay at the one substation being insufficient to cause actuation of relays at other substations connected with the line, whereby the telephonic apparatus at the other substations is maintained in an inoperative condition, and means at the one substation for causing reinclusion in circuit of the high resistance, whereby the current flow will be rendered sufficient to actuate other relays connected with the line.

6. In a telephone system, the combination with a party line, of a plurality of substations connected therewith, a relay at each substation, switching apparatus at each substation for closing circuits through said relay, telephonic apparatus at each substation, means for rendering said telephonic apparatus inoperative when said relay is inert, a source for providing current for the relay circuits upon actuation of the switching mechanism, and a high resistance and a low resistance path for said relay, actuation of the switching apparatus at one substation

- causing current flow to energize the relay, whereby the telephonic apparatus is rendered operative and whereby the high resistance path is removed from circuit and the low resistance path maintained to cause energization of the relay, the current flow from said source being insufficient to cause actuation of other relays upon actuation of the switching mechanism at other substations.
7. In a telephone system, the combination with a party line, of a plurality of substations connected therewith, a relay at each substation, switching apparatus at each substation for closing circuits through said relay, telephonic apparatus at each substation, means for rendering said telephonic apparatus inoperative when said relay is inert, a source for providing current for the relay circuits upon actuation of the switching mechanism, a high resistance and a low resistance path for said relay, actuation of the switching apparatus at one substation causing current flow to energize the relay, whereby the telephonic apparatus is rendered operative and whereby the high resistance path is removed from circuit and the low resistance path maintained to cause energization of the relay, the current flow from said source being insufficient to cause actuation of other relays upon actuation of the switching mechanism at other substations, and means at the one substation for causing effectiveness of the high resistance path, whereby the current flow will be sufficient to actuate the relays at the other substations.
8. In a telephone system, the combination with a party line, of a plurality of substations connected therewith, a relay and telephonic apparatus at each substation, a source for supplying current to the line and substations, switching mechanism at each substation for connecting said source with said relay, a comparatively low resistance winding for said relay, and a high resistance initially included in the relay circuit upon actuation of the switching mechanism, said telephonic apparatus being short circuited when the relay is inert, energization of the relay causing opening of said short circuit to render the telephonic apparatus operative and causing said resistance to be rendered ineffective, the current flow from said source when a relay at one substation is energized being insufficient to cause actuation of a relay at any other substation through the high resistance initially included in circuit therewith.
9. In a telephone system, the combination with a party line, of a plurality of substations connected therewith, a relay and telephonic apparatus at each substation, a source for supplying current to the line and substations, switching mechanism at each substation for connecting said source with said relay, a comparatively low resistance winding for said relay initially included in the relay circuit upon actuation of the switching mechanism, said telephonic apparatus being short circuited when the relay is inert, energization of the relay causing opening of said short circuit to render the telephonic apparatus operative and causing said resistance to be rendered ineffective, the current flow from said source when a relay at one substation is energized being insufficient to cause actuation of a relay at any other substation through the high resistance initially included in circuit therewith, a high resistance initially included in the relay circuit upon actuation of the switching mechanism, said telephonic apparatus being short circuited when the relay is inert, energization of the relay causing opening of said short circuit to render the telephonic apparatus operative and causing said high resistance to be rendered ineffective, the current flow from said source when a relay at one substation is energized being insufficient to cause actuation of a relay at any other substation through the high resistance initially included in circuit therewith, and independent means at each substation for causing reconnection of said resistance in circuit whereby there will be sufficient current flow to actuate the relay at another substation.
10. In a telephone system, the combination with a party line, of a plurality of substations connected therewith, a source of current for supplying the line and the substations, telephonic apparatus and switching apparatus at each substation, and a relay at each substation provided with a low resistance and a high resistance winding, said relay when inert causing closure of a short circuit path about the telephonic apparatus, said relay upon actuation of the switching mechanism being initially energized through both windings, actuation thereupon of the relay causing opening of said short circuit and the closure of a short circuit about said high resistance winding, whereby the relay is maintained in an energized condition through the low resistance winding and the telephonic apparatus maintained in an operative condition, the current from said source when the relay at the one substation is thus energized being insufficient to cause actuation of the relay at any other substation through the high resistance winding thereof, whereby the telephonic apparatus at all other substations is maintained inoperative.
11. In a telephone system, the combination with a party line, of a plurality of substations connected therewith, a source of current for supplying the line and the substations, telephonic apparatus and switching apparatus at each substation, a relay at each substation provided with a low resistance and a high resistance winding, said relay when inert causing closure of a short circuit path about the telephonic apparatus, said relay upon actuation of the switching mechanism being initially energized through both windings, actuation thereupon of the relay causing opening of said short circuit and the closure of a short circuit about said high resistance winding, whereby the relay is maintained in an energized condition through the low resistance winding and the telephonic apparatus maintained in an operative condition, the current from said source when the relay at the one substation is thus energized being insufficient to cause actuation of the relay at any other substation through the high resistance winding thereof, whereby the telephonic apparatus at all other substations is maintained inoperative.

- source when the relay at the one substation is thus energized being insufficient to cause actuation of the relay at any other substation through the high resistance winding thereof, 5 whereby the telephonic apparatus at all other substations is maintained inoperative, and additional switching means at the one substation whereby said high resistance winding may be reincorporated in circuit whereby 10 sufficient current may flow to energize the relay at any other substation to render the telephonic apparatus thereat operative.
12. In a telephone system, the combination with a party line, of a plurality of sub- 15 stations connected therewith, telephonic apparatus and circuit changing switching means at each substation, a relay at each substation provided with a low resistance and a high resistance winding, a source of 20 current for supplying the line and the sub- stations, and an armature for said relay adapted when inert to close a short circuit path about the telephonic apparatus, both windings upon actuation of the circuit chang- 25 ing apparatus being initially effective to- 30 ward energizing said relay, actuation of said relay thereupon causing attraction of the armature, whereby the short circuit about the telephonic apparatus is opened and whereby the high resistance winding is rendered in- 35 effective and the relay maintained energized by virtue of the low resistance winding.
13. In a telephone system, the combination with a party line, of a plurality of sub- 40 stations connected therewith telephonic apparatus and circuit changing switching means at each substation, a relay at each substation provided with a low resistance and a high resistance winding, a source of 45 current for supplying the line and the sub- stations, and an armature for said relay adapted when inert to close a short circuit path about the telephonic apparatus, both windings upon actuation of the circuit chang- 50 ing apparatus being initially effective to- 55 ward energizing said relay, actuation of said relay thereupon causing attraction of the armature, whereby the short circuit about the telephonic apparatus is opened and whereby the high resistance winding is rendered in- 60 effective and the relay maintained energized by virtue of the low resistance winding, the current flow from said source when the low resistance path at a substation is active being insufficient to cause actuation of the relay at any other substation through the high resistance winding thereof, whereby the telephonic apparatus at any other substation is maintained inoperative.
14. In a telephone system, the combination with a party line, of a plurality of sub- 65 stations connected therewith, telephonic apparatus and circuit changing switching means at each substation, a relay at each 70 substation provided with a low resistance and a high resistance winding, a source of current for supplying the line and the sub- 75 stations, an armature for said relay adapted when inert to close a short circuit path about the telephonic apparatus, both winding upon actuation of the circuit changing apparatus being initially effective toward energizing said relay, actuation of said relay thereupon causing attraction of the armature, whereby the short circuit about the telephonic apparatus is opened and whereby the high resistance winding is rendered ineffective and the relay maintained energized by virtue of the low resistance winding, the current flow from said source when the low resistance path at a substation is active being insufficient to cause actuation of the relay at any other substation through the high resistance winding thereof, whereby the telephonic apparatus at any other substation is maintained inoperative, and additional switching means for again rendering the high resistance winding effective whereby the current becomes of sufficient strength to actuate other relays.
15. In a telephone system, the combination with a party line, of a plurality of sub- 80 stations connected therewith, a source of current for supplying the line and substations, telephonic and switching apparatus at each substation, a relay at each substation 85 provided with a low resistance and a high resistance winding, an armature for said relay adapted when inert to close a short circuit path about said telephonic apparatus, actuation of said switching apparatus caus- 90 ing an initial current flow through a path including the high resistance winding, energization thereupon of the relay causing attraction of the armature, whereby the short circuit path about the telephonic apparatus 95 is open and whereby a short circuit path is closed about the high resistance winding, the relay being maintained energized solely through the low resistance winding, and an additional switch included in the short circuit path about the high resistance winding, 100 actuation of said additional switch causing reincorporation in circuit of the high resistance winding.
16. In a telephone system, the combination with a party line, of a plurality of sub- 105 stations connected therewith, a source of current for supplying the line and substations, telephonic and switching apparatus at each substation, a relay at each substation 110 provided with a low resistance and a high resistance winding, an armature for said relay adapted when inert to close a short circuit path about said telephonic apparatus, actuation of said switching apparatus caus- 115 ing an initial current flow through a path including the high resistance winding, energization thereupon of the relay causing attraction of the armature, whereby the short circuit path about the telephonic apparatus 120 is open and whereby a short circuit path is closed about the high resistance winding, the relay being maintained energized solely through the low resistance winding, and an additional switch included in the short circuit path about the high resistance winding, 125 actuation of said additional switch causing reincorporation in circuit of the high resistance winding.

is open and whereby a short circuit path is closed about the high resistance winding, the relay being maintained energized solely through the low resistance winding, the resistance of the low resistance winding being sufficiently low to prevent sufficient current flow through other substation relays to cause actuation thereof, whereby the telephonic apparatus at other substations is maintained 5 inoperative, and an additional switching mechanism included in the short circuit path about the high resistance winding, actuation of said switching mechanism causing re-inclusion in circuit of the high resistance winding, whereby sufficient current may flow to 10 actuate other relays connected in circuit at other substations.

17. In a telephone system, the combination with a party line, of a plurality of substations connected therewith, telephonic apparatus and switching mechanism at each substation, a relay at each substation having a low resistance and a high resistance winding, a source of current for supplying the line and substations, means for normally rendering the telephonic apparatus at each substation inoperative, the current flow upon actuation of the switching mechanism at only one substation being sufficient to cause active energization of the relay through the 20 high resistance winding, means upon energization for maintaining actuation of the relay solely through the low resistance winding, independent means for rendering the high 25 resistance winding effective, and a condenser 30 adapted to be shunted about the relay windings.

18. In a telephone system, the combination with a party line, of a plurality of substations connected therewith, a source of current for supplying the line and substations, telephonic apparatus and switching apparatus at each substation, a relay at each substation having a low resistance and a high 35 resistance winding, actuation of the switching apparatus at one substation causing current flow through the high resistance winding whereby said winding is initially effective in causing actuation of the relay, actuation of 40 the relay causing the high resistance winding to become ineffective and the relay maintained in an energized condition solely by the low resistance winding, the telephonic apparatus at each substation being effective 45 only upon energization of the corresponding relay, the current flow, however, from said source being insufficient upon energization of one relay through the low resistance path to sufficiently energize any other relay connected with the line, whereby the telephonic apparatus at other substations is maintained 50 inoperative, means at the one substation for re-including the high resistance winding in circuit whereby sufficient current flow may 55 pass through another relay to render the 60

telephonic apparatus controlled thereby operative, and whereby two subscribers connected with the same line may converse, and a condenser at the substations connected to remove the impedance effect of the windings 70 from the telephonic circuit.

19. In combination, a telephone line connecting a plurality of stations, a source of current connected between the two sides of the telephone line, telephonic apparatus at 75 each station, an electromagnet at each station, a high resistance energizing circuit for said electromagnet, an energizing circuit of decreased resistance for said electromagnet, mechanism controlled by each electromagnet 80 serving normally to render inoperative the associated telephonic apparatus and when actuated by the energization of the associated electromagnet to render operative 85 said telephonic apparatus, a manual switch at each substation serving when actuated to close the high resistance energizing circuit through said electromagnet in bridge of the telephone line, and means controlled by each electromagnet and serving when actuated 90 through its high resistance energizing circuit to close the energizing circuit of decreased resistance through said electromagnet in bridge of the telephone line said circuit including the telephonic apparatus. 95

20. In combination, a telephone line connecting a plurality of stations, a source of current connected between the two sides of the telephone line, telephonic apparatus at 100 each station, an electromagnet at each station, a high resistance energizing circuit for the electromagnet, an energizing circuit of decreased resistance for the electromagnet, switching means controlled by each electromagnet to govern the operative connection 105 of the associated telephonic apparatus with the line, a switch at each substation serving when actuated to close the high resistance energizing circuit through the winding of the associated electromagnet, and switching 110 mechanism controlled by each electromagnet and adapted when actuated by the associated electromagnet to establish through said electromagnet the energizing circuit of decreased resistance and including the telephonic apparatus. 115

21. In combination, a telephone line connecting a plurality of stations, a source of current connected between the two sides of the telephone line, telegraphic apparatus including a transmitter at each station, an electromagnet at each station, a high resistance energizing circuit for the electromagnet, an energizing circuit of decreased resistance for the electromagnet, mechanism 120 controlled by each electromagnet serving normally to render inoperative the associated telephonic apparatus and when actuated by the energization of the associated 125 electromagnet to render operative said tele- 130

phonic apparatus, a manual switch at each substation serving when actuated to close the high resistance energizing circuit through said electromagnet in bridge of the telephone line, means controlled by each electromagnet and serving when actuated through its high resistance energizing circuit to close the energizing circuit of decreased resistance through said electromagnet in bridge of the telephone line, and means for including a winding of the electromagnet at any station in a circuit supplying current to the associated transmitter.

22. In combination, a telephone line connecting a plurality of stations, a source of current connected between the two sides of the telephone line, telephonic apparatus including a transmitter at each station, an electromagnet at each station, a high resistance energizing circuit for the electromagnet, an energizing circuit of decreased resistance for the electromagnet, switching means controlled by each electromagnet to govern the operative connection of the associated telephonic apparatus with the line, a switch at each substation serving when actuated to close the high resistance energizing circuit through the winding of the associated electromagnet, switching mechanism controlled by each electromagnet and adapted when actuated by the associated electromagnet to establish through said electromagnet the en-

ergizing circuit of decreased resistance, and means located at each station for including a winding of the electromagnet at that station in a circuit supplying current to the associated telephone transmitter.

23. In a lock-out device, a relay, means for bringing said relay into circuit at a subscriber's station, a switch operated by said relay to bring the subscriber's talking outfit into circuit when operated, said relay having two energizing coils normally in series, and means for cutting out one of the coils when the relay is operated, substantially as and for the purpose specified.

24. In a lock-out for party-line telephone system, a main switch, a relay adapted by the operation of said main switch to be bridged across the line, and a talking circuit adapted by the operation of said relay to be also bridged across the line, energizing coils in series on said relay, and means for cutting out one of said coils when the relay is operated to connect the talking outfit, substantially as specified.

In witness whereof, I hereunto subscribe my name this fifteenth day of February A. D., 1905.

ARTHUR F. POOLE.

Witnesses:

JASON C. STAMP,
G. C. BROWNE.
